LIGHTING FIXTURE

Dominic A. Saporito, Birmingham, and Norbert T. Kuypers, Warren, Mich., assignors to Wakefield Corporation, Detroit, Mich., a corporation of Michigan

Filed Aug. 29, 1962, Ser. No. 71,485

Term of patent 14 years

(Cl. D48—4)

FIG. 1

FIG. 2

FIG. 3

FIG. 4

FIG. 1 is a perspective view of a lighting fixture showing our new design; and

FIGS. 2, 3, and 4 are side elevation, front elevation, and top plan views, respectively with the globe omitted for convenience of illustration.

The rear is substantially flat. The dominant features of our design reside in the portions shown in full lines.

We claim:

The ornamental design for a lighting fixture as shown and described.
